BRIDGE CONTRACT MINDER

G. Phillips Mahood, 285 Buckingham Drive,
Bethlehem, Pa. 18017

Filed Feb. 6, 1974, Ser. No. 439,899

Term of patent 3½ years

Int. Cl. D21—01

U.S. Cl. D34—13 A

Fig. 1

Fig. 2

FIG. 1 is a top plan view of the bridge contract minder embodying my new design.

FIG. 2 is a side elevational view taken on line 2—2 of FIG. 1.

FIG. 3 is a side elevational view taken on line 3—3 of FIG. 1.

I claim:

The ornamental design for a bridge contract minder, as shown.
